UNITED STATES PATENT OFFICE.

JOHN K. VAUGHN, OF SANFORD, FLORIDA.

SPLITTING-MACHINE.

1,250,054.

Specification of Letters Patent. Patented Dec. 11, 1917.

Application filed January 10, 1917. Serial No. 141,591.

To all whom it may concern:

Be it known that I, JOHN K. VAUGHN, a citizen of the United States, and a resident of Sanford, in the county of Seminole and State of Florida, have invented an Improvement in Splitting-Machines, of which the following is a specification.

My invention is an improvement in splitting machines, for cutting palmetto, palm and like leaves into strips, to prepare for use in making brooms.

In the drawings:

Figure 1 is a front view of the improved machine.

Fig. 2 is a top plan view.

Fig. 3 is a section on the line 3—3 of Fig. 2.

Fig. 4 is a section on the line 4—4 of Fig. 2.

Fig. 5 is a detail side view of the hinge connection.

Fig. 6 is a side view of a modified construction.

In the present embodiment of the invention a table is provided, comprising a top 1 and suitable supporting legs 2, which are braced against the table by inclined braces shown at 3. A portion of the front of the top is cut away, as shown, to facilitate access of the operator to the parts to be later described and a hinge plate 4 is connected with the top of the table, the said plate being supported by a block 5, in order to space the plate above the top of the table. A needle bar 6 is hinged to the plate 4, by means of a bolt and nut 7, and this bar, as shown, consists of two similar sections, the bar as a whole being curved at its outer end, so that the free end of the bar extends to the front edge of the table beyond the cut away portion, as shown, the said cut away portion being at the block 5.

A plate spring 8 is secured to the plate 4 at one end, and the free end of the spring 45 overlies the inner end of the bar, as shown in Fig. 5, to normally hold the said bar in the elevated position of Fig. 5. A series of needles 9 is carried by the bar, the said needles being arranged between the sections 50 and being secured to the sections by means of bolts and nuts 10 which are passed transversely through the registering openings in the sections, between the needles. These needles engage openings 11 in the table top, 55 and the free end of the bar, when the nee-

dles are in the recesses or sockets 11, is adapted to engage a stop 12 which is connected to one of the arms 13 of a U-shaped bracket, whose body 14 is secured to the table top with the arms depending. The 60 stop 12 is bolted to one of the arms, and a latch bar 15 is bolted to the other arm. This bar 15 is adapted to engage over the free end of the bar 6 when the said bar is in engagement with the stop to hold the bar 65 and the needles in operative position. This latch is released to permit the bars 6 to move upward under the influence of the spring 8, by means of a treadle 17.

This treadle is pivoted to one of the legs 70 of the table as indicated at 18, and is connected to the latch by a link 16. When the free end of the treadle is swung downward the latch is swung outward releasing the bar which immediately assumes the dotted line 75 position of Fig. 1. The treadle is returned to original position and normally held in such position by a coil spring 19, which is connected at one end to the table top and at the other to a link 20, the lower end of the 80 link being connected to the treadle.

The links 16 and 20 are of wire or the like, and the link 16 passes outwardly through an opening in the vertical portion of an angle bracket secured to the table top, 85 and this vertical portion has at its upper end a set screw 22 forming a stop, for limiting the outward movement of the latch. The said screw is threaded through the bracket and is engaged by lock nuts 23 on the outer 90 face of the vertical portion of the bracket.

In operation, with the parts in the dotted line position of Fig. 1, a leaf is placed upon the table. The bar is now depressed manually, and the needles are driven through 95 the leaf into the sockets on the table. It will be noticed that the upper end of the latch is beveled, as shown at 24, so that as the bar descends the latch will be pushed aside and will engage over the end of the bar to hold 100 the same down on the table. To release the bar it is only necessary to press downward on the free end of the treadle and the latch will be drawn out of engagement with the bar and the spring 8 will swing the bar upward. The stripped leaf is removed and another inserted.

In Fig. 6 is shown a modified construction, wherein the table top 25 is provided with the needles 26, the said needles being insert- 110

ed in the top in any suitable or desirable manner. These needles may be arranged in a curve corresponding to that of the needles 9. A bar 27 is mounted in uprights 28 on the table for movement toward and from the needles, and this bar has sockets in its under face for receiving the points of the needles. Several leaves may be stripped at once.

10 It will be understood that the bar 27 in Fig. 6 may be hinged at one end if desired, and that the bar 6 in Fig. 1 may move vertically. The needles in Fig. 6 may be in the bar 27 instead of in the table, and in Fig. 1 15 the needles may be in the table instead of in the bar. A hinge may be arranged at either end to provide for right and left handed machines.

I claim:—

20 1. A splitting machine comprising a table, a bar hinged at one end to the table and provided with spaced needles, the table having sockets for receiving the points of the needles, a spring normally pressing the free end 25 of the bar upward to hold the needles out of contact with the table, latch mechanism for holding the bar with the needles in the sockets, and means for limiting the downward

movement of the bar, and means for releasing the latch.

2. A splitting machine comprising a table, a bar hinged at one end to the table, said bar carrying spaced needles, and being curved to extend to the front of the table at its free end, latch mechanism for holding the bar with the needles in contact with the table, a spring for lifting the bar, and means for releasing the latch.

3. A splitting machine comprising a table, a bar hinged at one end to the table, said bar carrying spaced needles, and being curved to extend to the front of the table at its free end, latch mechanism for holding the bar with the needles in contact with the table, and means for releasing the latch.

4. A splitting machine comprising a table, a bar hinged at one end to the table and provided with spaced needles for transfixing a leaf laid upon the table, releasable means for holding the bar with the needles in contact with the table, and a spring for lifting the bar.

JOHN K. VAUGHN.
